UNITED STATES PATENT OFFICE.

FRANK A. CONRAD, OF ST. PAUL, MINNESOTA.

HOT-AIR FURNACE.

Application filed October 4, 1926, Serial No. 139,390. Renewed April 18, 1928.

My invention relates to hot air furnaces, and an object is to provide a furnace of this type in which the heat going to the various rooms is equally distributed or automatically 5 equalized so that all of the rooms in the building will receive their proper share of heat regardless of conditions tending to cause a greater flow of heat to some of the rooms than to other rooms. Another object 10 is to provide for moistening and cleaning the heated air which is supplied to the rooms. Another object is to conserve heat and prevent waste of fuel. Another object is to centralize and produce an even draft 15 through the fire or grates. Another object is to cause the gases, smoke, and flame to rise to the top of the combustion chamber and then be deflected downwardly before passing to the exit leading to the chimney 20 which action tends to burn the gases more completely and to force the flame into direct contact with the radiating surface of the furnace.

The full objects and advantages of my 25 invention will appear in connection with the detailed description thereof, and the novel features of my inventive idea will be particularly pointed out in the claims.

In the accompanying drawings which illustrate a practical embodiment of my invention,—

Fig. 1 is a view of the furnace in central vertical section. Fig. 2 is a top plan view. Fig. 3 is a view in horizontal section on the 35 line 3—3 of Fig. 1. Fig. 4 is a plan view of the top members of the casings looking at the inside thereof before these members are attached to the body of the furnace. Fig. 5 is a fragmentary perspective view of one 40 of the casings. Fig. 6 is a partial view of a water trough taken substantially on the line 6—6 of Fig. 1 but removed from the furnace.

Referring to the construction shown in the 45 drawings, the numeral 10 designates the firebox of a hot-air furnace having a main wall or casing 12 toward the lower end of which the firebox 10 and a grate 14 are located, the ashpit 16 and its door 18 being 50 below the grate as usual. The casing 12 is closed at its top to produce a combustion chamber 19. Surrounding and spaced from the furnace casing 12 is an inner casing 20 formed in sections as shown in Fig. 5, the 55 sections having inturned flanges 22 which engage each other to form a series of radi-

ally extending partitions between the casings 12 and 20. A band 24 secured around the sections hold them in place. The casing 20 is provided with a conical top 26 60 which has a depending flange fitting over the upper end of the casing, this top being provided with openings 28 fitted with short outwardly extending pipe sections 30. Concentrically spaced around the casing 20 is an intermediate casing 32 which is provided with a conical top 34 riveted thereto. The space between the apices of the conical tops 26 and 34 is filled with heat insulating material 36 such as asbestos. A horizontal plate 70 38 extends across the conical top 26 considerably below its apex so as to form a dead-air space 40. The conical top 34 is provided with a plurality of openings from which hot air pipes 42 extend. The pipe sections 30 75 are smaller than the pipes 42 and extend a short distance into the latter which at their lower ends are spaced concentrically around the sections 30 to provide the annular openings 43. Concentrically spaced around the 80 intermediate casing 32 is an outer casing 44 which is provided with a conical top 46 having openings, the edges of which are closely engaged by the hot air pipes 42. The top member 46 while of conical shape in general 85 does not extend to an apex but at its center is provided with an upwardly extending annular flange 48 for receiving the end of a cold air supply pipe 50. The top members 26 and 34 are maintained in properly spaced 90 relation by the interposed insulating material 36. The top members 34 and 46 are maintained in properly spaced relation by interposed spacing sleeves 52 through which bolts 54 pass. These bolts also pass through 95 the three top members so that the top structure is held together and may be handled as a unit with the pipe sections 30 secured in place while the members 42 of the hot air pipes may afterward be secured in place 100 or they may consist of comparatively short pipe sections for convenience in handling. The outer casing 44 if desired may consist of horizontal sections riveted together as shown in Fig. 1 with the joints between the 105 sections and the joint between the casing and the top member 46 covered by bands 56. Charging doors 58 and 60 are hinged to the outer casing adjacent suitable openings which extend through all of the casings. A smoke pipe 62 is shown secured to a smoke flue with which the furnace is provided. 110

The smoke flue consists of a horizontal member 64 and an upwardly inclined member 66. The member 64 passes through openings in the casings 20, 32, and 44 and has its inner 5 end telescopically engaging the outer end of the member 66. The inner end of the latter is turned so as to extend directly upward and is located centrally in the combustion chamber 19 with relation to the surrounding 10 wall thereof. The flue member 66 may be supported in the manner illustrated in Fig. 1, which shows two bolts 68 and 70 adjustably secured together, the bolt 68 being attached to the member 66 and the bolt 70 15 extending through the casing 12 and through a flange on the member 64. As will be understood particularly from Fig. 5, partition members 72 are secured to the upper ends of the partition flanges 22; the members 72 separating the space in the top member 26 below the plate 38 into compartments which constitute extensions of the compartments formed by the flanges 22. The outer 20 casing 44 has its lower end disposed in such 25 manner as to make a tight seal at the bottom while the casings 20 and 32 stop short of the bottom. As shown in Fig. 1, the lower end of the casing 44 fits tightly upon the outer wall of an annular water trough 30 74 resting upon the floor. This trough is made in sections with a gap adjacent the ash-pit door 18, the sections being secured together by a screw-threaded sleeve 76 so as to be in communication with each other. 35 Water may be supplied to the trough through a pipe 76 connected with the water system and having a shut-off valve 78 controlled by a float 80 in the trough.

The operation and advantages of my invention will be understood in connection 40 with the foregoing description. Cold or fresh air supplied in any suitable manner enters through the inlet pipe 50 and passes downwardly between the outer casing 44 and the intermediate casing 32 and after 45 coming into contact with the water in the trough 74 passes upwardly between the furnace casing 12 and the inner casing 20 through the compartments formed by the radial partitions constituted by the flanges 22 and the members 72. The space between 50 the two casings 20 and 32 constitutes an insulating chamber. The air when it passes over the water in the trough, takes up moisture and is freed from impurities. From 55 the compartments surrounding the furnace casing, the heated and moistened air passes through the short pipe sections 30 into the hot air pipes 42 which supply hot air to the various rooms of the building. Under ordinary working conditions of the furnace, the pipes 42 will receive all or the greater portion of their supply of air through the short pipe sections 30. However, if conditions 60 arise so that one or more of the pipes 42

start to convey more than their proper amount of heated air whereby the suction through such pipes is materially increased, then some of the incoming air will pass up between the casings 20 and 32 and through 70 the annular openings 43 around the pipe sections 30, thereby reducing the amount of heated air passing through the sections 30. This arrangement, therefore, acts as an equalizer to keep the rooms heated by the 75 furnace at a uniform temperature regardless of extraneous conditions such as the direction of the wind. It is contemplated that there will be one of the compartments previously referred to in association with a hot 80 air supply pipe for each room of the building. The cold air when it leaves the surface of the water in the trough is thus divided into portions corresponding to the rooms so that the hot air for each room is separately heated. Moisture is taken by the air before the latter is heated which adds considerably to the heat absorption property of the air. The entrance into the draft flue 66 is located near the center of the combustion 90 chamber and is so arranged that the smoke and flame first pass to the top of the combustion chamber before they enter the flue on their way to the chimney. This action tends to burn the gases more completely and also forces the gases and flame into direct contact with the radiating surface formed by the casing 12 which surrounds the combustion chamber.

I claim:

1. In a hot air furnace, the combination of an outer casing surrounding and spaced from the furnace casing and sealed at the bottom, inner and intermediate concentric casings interposed between said outer casing and the furnace casing, said inner and intermediate casings stopping short of the bottom of the furnace, means for supplying cold air to the space between said outer and intermediate casings, hot air pipes secured around openings in the upper portion of said intermediate casing, and pipe sections secured around openings in the upper portion of said inner casing, said pipe sections extending into said hot air pipes respectively and being internally spaced therefrom whereby passages are provided from the space between said intermediate and inner casings into said hot air pipes.
2. In a hot air furnace, the combination of an outer casing surrounding and spaced from the furnace casing and sealed at the bottom, inner and intermediate concentric casings interposed between said outer casing and the furnace casing, said inner and intermediate casings stopping short of the bottom of the furnace, a cold air pipe leading into the upper portion of the space between said outer and intermediate casings, hot air pipes secured around openings in the upper 120

portion of said intermediate casing, and pipe sections secured around openings in the upper portion of said inner casing, said pipe sections extending into said hot air pipes 5 respectively and being internally spaced therefrom whereby passages are provided from the space between said intermediate and inner casings into said hot air pipes.

3. In a hot air furnace, the combination 10 of an outer casing surrounding and spaced from the furnace casing, a water trough around the lower end of the furnace casing and with which the lower end of said outer casing makes a tight fit, inner and intermediate concentric casings interposed between said outer casing and the furnace casing, said inner and intermediate casings stopping short of the water trough, means for supplying cold air to the space between said 15 outer and intermediate casings, hot air pipes secured around openings in the upper portion of said intermediate casing, and pipe sections secured around openings in the upper portion of said inner casing, said 20 pipe sections extending into said hot air pipes respectively and being internally spaced therefrom whereby passages are provided from the space between said intermediate and inner casings into said hot air pipes.

4. In a hot air furnace, the combination 25 of an outer casing surrounding and spaced from the furnace casing and sealed at the bottom, inner and intermediate concentric casings interposed between said outer casing and the furnace casing, said inner and intermediate casings stopping short of the bottom of the furnace, radially extending 30 partitions between said inner casing and the furnace casing, means for supplying cold air to the space between said outer and intermediate casings, hot air pipes secured around openings in the upper portion of said intermediate casing, and pipe sections 35 secured around openings in the upper portion of said inner casing, said pipe sections extending into said hot air pipes respectively and being internally spaced therefrom whereby passages are provided from the space between said intermediate and inner casings into said hot air pipes.

50

5. In a hot air furnace, the combination 55 of an outer casing surrounding and spaced from the furnace casing and sealed at the bottom, inner and intermediate concentric casings interposed between said outer casing and the furnace casing, said inner and intermediate casings stopping short of the bottom of the furnace, conical top members 60 for said outer, inner, and intermediate casings, a cold air pipe leading into the apex of said outer casing and directly over the apex of said intermediate casing whereby the incoming air is caused to spread out, hot air pipes secured around openings in the top member of said intermediate casing, and pipe sections secured around openings in the top member of said inner casing, said pipe sections extending into said hot air pipes respectively and being internally 65 spaced therefrom whereby passages are provided from the space between said intermediate and inner casings into said hot air pipes.

6. In a hot air furnace, the combination 70 of an outer casing surrounding and spaced from the furnace casing and sealed at the bottom, inner and intermediate concentric casings interposed between said outer casing and the furnace casing, said inner and intermediate casings stopping short of the bottom of the furnace, means for supplying cold air to the space between said outer and intermediate casings, hot air pipes secured around openings in the upper portion of 75 said intermediate casing, pipe sections secured around openings in the upper portion of said inner casing, said pipe sections extending into said hot air pipes respectively and being internally spaced therefrom 80 whereby passages are provided from the space between said intermediate and inner casings into said hot air pipes, and a smoke flue whose upper end is centrally disposed in the combustion chamber and which inclines downwardly to the furnace casing and passes horizontally through said inner, intermediate and outer casings.

In testimony whereof I hereunto affix my signature.

FRANK A. CONRAD.
